ARTICLE EJECTOR FOR VENDING MACHINES

Mario Caruso, Maplewood, N. J., assignor to
C-Eight Laboratories, Newark, N. J.Original application December 26, 1946, Serial No.
718,529. Divided and this application December 10, 1947, Serial No. 790,842

8 Claims. (Cl. 312—68)

1

This invention relates generally to vending machines, and particularly to the article ejector structure for such machines, and represents one of the divisions of co-pending application Serial No. 718,529, for Vending machine, filed by me December 26, 1946.

As indicated above, the present invention deals with an article ejector mechanism for vending machines and is especially adapted for the type of machines wherein articles of merchandise to be dispensed are arranged in columns, within suitable magazines, and in which latter the articles are supported by mobile platforms equipped with a mechanism for urging these platforms and the merchandise supported by them to progress in upward direction. The ejector structure is adapted for a reciprocating movement transversely to the upwardly moving columns of the merchandise so that during one operating cycle the ejector structure moves from its starting position first in one, or a forward direction, until it comes to a stop, whereupon it moves in reverse or backward direction until it reassumes its starting position.

The principal objects of the present invention are the provision of an article ejector structure for vending machines of the type indicated, including a reciprocating carriage movable transversely in respect to the upwardly moving columns of merchandise, and in which carriage are mounted individual ejector elements corresponding in number to that of the merchandise columns, and wherein such ejector elements are normally kept in their inoperative position so that they clear the merchandise held in said columns, and wherein means are provided for releasing any one of the ejector elements to its operative, article engaging position, for ejecting an article during the initial movement of the carriage, and wherein motor driven means are provided for actuating said carriage to move first in one and then in reverse direction, and wherein other means are provided for resetting a released ejector element during the first, initial or forward movement of the carriage, and wherein a number of manually and automatically operable switch devices are employed for controlling the operation of said carriage actuating means, at least one of the automatic switch devices being adapted to become operated through the movement of the carriage, while at least another automatic switch device is adapted to be closed and opened by the movement of the carriage actuating means.

The foregoing and numerous other objects and additional advantages of the present invention will become more fully understood from the en-

2

suing description, in conjunction with the accompanying drawings, wherein:

Fig. 1 is a fragmental plan view of a carriage in accordance with the present invention;

Fig. 2 is a fragmental rear elevation thereof with its individual ejector elements in inoperative, elevated position;

Fig. 3 is a fragmental rear elevation of the carriage with an ejector element in its operative, article engaging position;

Fig. 4 is a fragmental illustration, partly in section of an open vending machine casing, showing a few article magazines and a portion of the carriage in front elevation and the ejector elements 15 of the carriage in inoperative position;

Fig. 5 is a fragmental side elevation of and a vertical section through parts of the vending machine frame and through parts of the carriage, and disclosing an ejector element in its inoperative position, and the starter switch in its initial or readiness position;

Fig. 6 is a similar illustration to that of Fig. 5 with the ejector element in released, operative, article engaging position, and the starter switch in 25 its motor-energizing position;

Fig. 7 is a side elevation of the carriage, partly in section, during its initial or forward movement, and showing an ejector element in engagement with an article, prior to ejecting the latter;

Fig. 8 is a view similar to that illustrated in Fig. 7 with the carriage shown in its extreme forward end position and with the ejector element reset to its inoperative position;

Fig. 9 is a side elevation, partly in section, 35 through the carriage, showing the latter in its initial or starting position with the ejector element prevented from being released to its operative position by a projection of the article support, which latter has progressed to its uppermost position in an emptied article magazine;

Fig. 10 is a fragmental side elevation of the motor circuit holding switch and of a portion of the mechanism for actuating it;

Fig. 11 is a top view of the motor and of the holding switch; and

Fig. 12 is an electric diagram with portions of the vending machine mechanism indicated therein.

Referring to Figs. 4 and 9, numeral 10 designates a vending machine casing in which is arranged a plurality of magazines 11 for the reception of columns of merchandise articles 12, supported by platforms 13, the latter being equipped with instrumentalities for moving the platforms and the merchandise supported by

them in upward direction. Each platform has a rear extension 14, see Fig. 9, provided with an upward projection 15 which is adapted to prevent the release of the individual ejector elements to their operative, article-engaging position when the magazines are empty and platforms 13 assume their uppermost position.

The ejector carriage, as shown in Figs. 1 to 9, is generally indicated at 16, and comprises a substantially channel-shaped structure extending over the major top portion of the vending machine. The carriage is supported by rollers 17, mounted in suitable guideways arranged in the framework of the vending machine, and extending from the ends of the carriage, and which ends constitute gear racks 18, engaged by pinions 19, as clearly seen in Figs. 7, 8, and 9. These pinions are keyed to shaft 20 journaled in the framework of the machine. One end of the shaft projects outwardly and upon this outer shaft extension is mounted another pinion or gear 21, as seen in Fig. 12. Gear 21 is engaged by a gear segment 22, forming a part of the actuating mechanism 23 for carriage 16. This mechanism is driven by a motor 24, seen in Figs. 10 to 12, inclusive. Carriage 16 is adapted to move, during one operating cycle, from its starting position first in one, the forward direction, and then in reverse or backward direction until it reassumes its starting position. This movement is imparted to the carriage by a swinging motion of gear segment 22, first in anticlockwise or left hand and then in clockwise or right hand direction, which movement to the segment is caused by a crank 25 driven by motor 24, see Figs. 10 to 12. This crank has a cam 26 adapted to engage a lever 27 by means of which a motor circuit holding switch 28 is closed, before another switch, controlling the motor circuit, opens, as will be presently explained.

The carriage

The structure of the carriage includes a channel formation 29, extending between the two spaced gear racks 18 forming its ends.

The carriage operates in what may be termed a well formation provided at the upper part of the vending machine casing 10. Within the carriage channel there are arranged in spaced relation to one another several individual ejector units or ejector elements, indicated generally at 30, as clearly seen in Figs. 1 to 4. These ejector elements are pivotally mounted at 31 between suitable lugs extending from channel 29, and comprise a forward article engaging portion 32 and an upwardly bent rear extension 33, the upper end 34 of which is reduced for engagement with an aperture 35 provided in a detent 36, which latter is pivotally mounted on a shaft 37. The article engaging portion 32 of the ejector element has an upwardly swung extension 38 supporting a pair of rollers 39. All of the ejector elements are urged by coil springs 40 toward their operative position, seen in Figs. 6 and 7, but are normally held in their inoperative position shown in Fig. 5. In that position the ejector elements are kept by means of upper reduced end 34 of their rearward extension 33, which end is engaged by aperture 35 of detent 36. A coil spring 41 urges the detents in downward direction and into engagement with extension 33.

Also arranged in channel formation 29 is an elongated bar 42 pivotally mounted on a shaft 43. Bar 42 extends the entire length of the carriage. A coil spring 44, shown in Fig. 1, urges

bar 42 into engagement with a stop 45. Extending from one portion of bar 42 is a bracket 46 in which is mounted a dielectric roller 47, the purpose of which will be explained presently.

In the frame of the machine, above carriage 16 when the latter is in its starting position, there is provided a box-like casing 48, in which is housed a row of solenoids 49, one above each detent 36. When one of these electromagnets becomes energized it attracts its corresponding detent, thus causing it to disengage the reduced portion 34 of rear extension 33 of the corresponding ejector element, whereby the element is released and assumes its operative, article engaging position.

The number of ejector elements 30 and the number of electromagnets 49 corresponds to the number of article magazines 11. Below the solenoid casing 48, and also below the carriage in its starting position, there is mounted a starter switch 50, see Figs 5 and 6, composed of a movable contact blade 51 and two relatively fixed but resilient contact blades 52 and 53. Movable blade 51 is pivoted at 54 and is provided with a coil spring 55 which urges the blade towards fixed contact blade 53. The upper end of blade 51 is normally engaged by dielectric roller 47 mounted in brackets 46 of bar 42. Roller 47 in engaging movable contact blade 51, as shown in Fig. 5, holds that blade against fixed blade 52. When any one of the ejector elements is released by its detent, the rearward extension 33 of the element will swing bar 42 against the tension of its spring 44 to the position shown in Fig. 6, at which moment roller 47 disengages movable blade 51 and permits its spring 55 to swing it forwardly, thereby causing blade 51 to engage fixed contact blade 53.

Below carriage 16 there extends a plate 56 from the rear towards the front of the machine and in this plate are provided longitudinal slots or spare-outs 57 as clearly seen from Figs. 4 to 9. These spare-outs serve for accommodating the article engaging portions 32 of ejector elements 30 when they are brought to their operative position, as shown in Figs. 6 and 7, and at which position of the ejector elements their rollers 39 come to rest against the edges of spare-outs 57, whereby the ejector elements are held in their correct, operative, article-engaging position.

Referring now to Figs. 7, 8 and 9, it will be observed that plate 56 is bent upwardly towards the front of the machine, as shown at 58, and at the upper end of the incline there is formed an elevated portion 59 constituting a narrow ridge or platform. When one of the elements 39 is released by detent 36, as shown in Fig. 6, its frontal article ejecting portion 32 drops into slot 57 and its rollers come to rest upon the edge of the slot. As now the carriage moves forward during the first movement of its working cycle, in the manner shown in Fig. 7, the upwardly bent part 38 of the element engages article 12 in magazine 11. As the movement of the carriage progresses, the article is discharged and the element becomes elevated as rollers 39 roll upon incline 58 until they come to rest on platform 59, in the manner shown in Fig. 8, at which moment the ejector element assumes its inoperative position 30 at which it is held by detent 36.

Referring now to Figs. 10 to 12, inclusive, motor 24 for driving mechanism 23, which latter actuates carriage 16, is provided with a gear transmission, denoted in Fig. 11 at 60, including a worm gear 75 arrangement 61 which drives a shaft 62 upon

which is mounted crank 25 terminating in a wedge-shaped cam 26. As stated previously, cam 26 is designed to engage switch operating lever 27. This lever is adapted, when actuated by cam 26, to close switch 28. This switch is a holding switch and consists of two pairs of blades 63 and 64 and 65 and 66. The first pair of blades 63 and 64 are connected to taps made in the winding of motor 24 through a resistance 67, which latter is shunted into the motor winding to slow down the speed of the motor when the carriage is returning to its starting position. Blades 65 and 66, when in engagement with one another, close the main motor circuit which is also controlled by starter switch 50, as will be presently evident.

Referring to Fig. 12, from crank 25 extends a connecting rod 68 in engagement with arm 69 for operating gear segment 22, which in turn engages gear 21 for actuating shaft 20 and thereby impart a reciprocating motion, by means of pinions 19 and gear racks 18, to the carriage structure. In Fig. 12 there is also disclosed a wiring diagram and the general organization of the different electrical devices employed.

In the wiring diagram are included three terminal blocks A, B and C. Each of the blocks is provided with aligned pairs of numbered terminals. Referring to block C, there are provided nine pairs of terminals, of which terminals 4 and 5, terminals 6 and 7 and terminals 8 and 9 are interconnected with one another. From terminal 9 extends a lead 70 to terminal 1 of terminal block B. From this lead branches off a lead 71 to a contact spring 72 of a coin counter, generally indicated at 73. This coin counter has three other contact springs 74, 75 and 76 which are connected, respectively, with terminals 2, 3 and 4 of terminal block B. The coin counter includes a contact plate 77 which, when brought beneath all four contacts, as shown, electrically connects all four contact springs. From terminals 2, 3 and 4 of terminal block B extend leads to three coin-denominating bars 78, 79 and 80, selectable by means of hand levers 81. These hand levers are connected with manually operable, normally open switches 82 and 83. The number of hand levers 81 and the number of manual switches corresponds to the number of solenoids 49. Each of these manually operated switches serves for momentarily closing one individual circuit for energizing one of the solenoids. From switches 82 and 83 extend leads to terminals 1 and 2 of terminal block A, and from there other leads 84 and 85 pass to one terminal of electromagnets numbered 1 and 2, respectively. The other terminals of the electromagnets are connected by means of lead 86 to terminal 5 of terminal block C.

Considering now starter switch 50, movable contact 51 is connected by lead 87 to terminal 6 of terminal block C. Fixed contact blade 52 is connected by lead 88 to terminal 5 of terminal block C, and stationary blade 53 of the switch is connected by lead 89 to terminal 3 of block C. From this terminal a lead 90 connects with switch blade 65 of holding switch 28, and continuing from that blade a lead 91 is connected with terminal 92 of motor 24. Switch blade 66, opposite blade 65, is connected by lead 93 to terminal 6 of block C. Switch blade 63 is connected by lead 94 to resistance 67 and from the resistance a lead 95 extends to winding tap 96 of the motor. Blade 64, opposite blade 63 of the switch, is connected by lead 97 with tap 98 of the motor, and terminal 99 of the motor is connected by lead 100 to terminal 8 of block C.

Operation

When carriage 16 is in its starting position (Fig. 5), all ejector elements 30 are in their inoperative position, being held in that position by their detents 36. At this starting position of the carriage movable contact 51 of starter switch 50 engages fixed contact 52, being held in that position by roller 47 of bar 42. At this position of the starter switch the electric connections of the device are in readiness for the starting operation, induced by the momentary closing of one of the manually operated switches. When, for instance, switch 82 is thus closed, its corresponding solenoid 1 becomes energized and attracts detents 36, whereby ejector element 30 is released to its operative position. The released ejector element swings bar 42 forwardly, whereby dielectric roller 47 disengages movable contact blade 51 of starter switch 50. By that disengagement of contact blade 51, the latter is caused by its spring to engage stationary contact 53, thus closing the circuit supplying energy to motor 24. As the motor is energized it turns shaft 62, whereby lever 68 is caused to operate arm 69, which latter in turn moves gear segment 22 in anticlockwise direction. Gear segment 22 being in engagement with pinion 21, motion is imparted by means of shaft 20 to pinions 19, which in turn move carriage 16 in forward direction by means of gear racks 18.

During this forward movement of the carriage, element 30, being now in its downward, operative, article-engaging position, will engage an article in the manner shown in Fig. 7, and will eject the article as indicated in Fig. 8, at which moment the carriage reaches its extreme forward end position. During the forward movement of the carriage ejector element 30 is caused to re-assume its inoperative position as shown in Fig. 8, at which position it is held by its detent 36.

The operating cycle of the carriage now continues in that gear segment 22 moves in right hand direction towards its original position. During that movement the carriage is brought back to its starting position. While on its way to that position roller 47 of bar 42 re-engages contact blade 51 of the starter switch, and the circuit controlled by that contact blade and stationary blade 53 is opened. Before such opening of the motor circuit takes place, wedge-shaped cam 26 engages actuating lever 27 of holding switch 28. This lever is normally held in its outward position, shown in Fig. 10, by switch blades 64 and 66. The outward movement of the lever is limited by an abutment 27' shown in that figure. As lever 27 is now forcibly pressed against the tension of contact blades 64 and 66 by the action of cam 26, the two pairs of contact blades close the motor circuit and shunt into that circuit resistance 67. Thus before movable contact blade 51 of starter switch 50 leaves stationary contact blade 53, the holding switch is closed and provides energy for the operation of the motor so that the carriage actuating mechanism can complete its function of moving the carriage to its starting position. At the same time the rotation of the motor is slowed down by the inclusion into the motor supply circuit of resistance 67. As crank 25 reassumes its original, inoperative position, it releases actuating lever 27 of holding switch 28, whereby the holding switch is caused to open, thus cutting off electric current to the motor.

The carriage having reached its starting position, mobile switch blade 51 of the starter switch

is again pressed into engagement with stationary contact 52 and renders the device ready for the next operating cycle caused by a temporary closing of any one of the manually operated switches controlling solenoids 49.

As stated previously, the articles in each magazine are propelled upwardly by platform 13 which is designed to automatically progress in upward direction, while supporting merchandise, until all the merchandise is exhausted. At that moment platform 13 comes in abutment with plate 56, as clearly seen in Fig. 9. In that position of platform 13 projection 15, extending above rear extension 14 of the platform, assumes a position beneath forward portion 32 of the ejector element and prevents the latter from dropping to its operative position, even though released by detent 36, when its corresponding solenoid becomes energized by a temporary closing of one of the solenoid switches, such as switches 82 and 83. Thus the carriage is prevented from being operated in case a solenoid controlling an ejector element of an empty magazine column becomes energized.

While in the drawings specific structures of the mechanism and a specific organization of such mechanisms is illustrated, it is quite obvious that changes and improvements may be incorporated in the device, without departing from the broad scope thereof, as defined in the annexed claims.

I claim:

1. In an article ejector structure for vending machines employing means for feeding upwardly articles of merchandise arranged in columns, a reciprocating carriage movable above and transversely in respect to the direction of movement of the merchandise columns, a plurality of individual ejector elements, one for each column, releasably mounted in said carriage but normally held in inoperative position above and clearing the merchandise, means for releasing one of the ejector elements to its operative position for engagement with an article of merchandise in one of the columns, means for actuating said carriage to move first in one and then in the reverse direction, and means for resetting the released ejector element, the first movement of the carriage causing the released element to eject the engaged article and to reset the element to its inoperative position, the reverse movement of the carriage placing the latter and its ejector elements to a starting position ready for the next operation.

2. In an article ejector structure for vending machines having article magazines equipped with means for supporting articles of merchandise in columns and for propelling the articles in upward direction, a reciprocatingly operative carriage for ejecting articles from the magazines, an electric motor, a plurality of switches controlling the operation of the motor, an actuating mechanism driven by the motor for moving said carriage first in one and next in the reverse direction, a plurality of individual article ejector elements pivotally mounted in said carriage and being normally retained in their inoperative position above the articles in the magazines, electric control means for releasing singly any one of the elements from their normal, inoperative position to their operative, article engaging position and for simultaneously closing one of said motor-controlling switches to energize said motor for driving said actuating mechanism, which latter is adapted to impart to said carriage the aforesaid two-directional movement; means for resetting a released ejector element to its normal, inoperative position during the first movement of the carriage, and

means for opening said one motor-controlling switch at the termination of the reverse movement of said carriage.

3. In an ejector structure for vending machines employing upwardly moving columns of merchandise articles, a reciprocating carriage movable above and transversely to the movement of said columns first in one and next in reverse direction, an actuating mechanism for imparting motion to said carriage, a motor for driving said mechanism; a plurality of individual ejector elements, one for each article column, releasably mounted in said carriage and normally held in inoperative position above and clearing the merchandise, but being adapted, when individually released, to drop to their operative position for engaging and ejecting an article when the carriage is actuated and completes its first movement in that one direction, means in the path of a released element for resetting it to its inoperative position during such first movement of the carriage after the ejection of an article; electromechanical means for releasing the elements to their operative position, a double switch controlling the operation of said motor and of said electromechanical ejector element releasing means, said carriage actuating mechanism having means for operating said double switch.

4. In an article ejector structure of the type indicated, a reciprocating carriage adapted, in completion of one working cycle, to move first in one direction, to eject an article, and next in reverse direction to its starting position, an actuating mechanism for the carriage, an electric motor for driving the mechanism; said carriage having a plurality of individually operable article ejector elements, each element comprising an article engaging portion and an extension, each element having spring means urging the element toward its operative, article engaging position; a plurality of detents for said element extensions and being adapted to normally engage the latter for retaining the elements in inoperative position; a plurality of electromagnets, one for each ejector element, and being adapted to attract said detents and thereby to cause the latter to disengage said element extensions, thus releasing the elements to assume their operative position; a double action starter switch controlling, in one position, circuits of the electromagnets, and in its other position the motor circuit; a holding switch for the motor circuit; said starter switch comprising two fixed contact blades and a spring actuated movable blade mounted between the fixed blades, the spring of the movable blade urging the latter toward one of the fixed blades; a control member for the movable switch blade adapted to normally engage the movable blade and to press the latter into contact with the other fixed blade, whereby all of the circuits of the electromagnets are held in readiness so that any one of the circuits may be closed for energizing its corresponding electromagnet; said element extension being adapted, when released by its detent, upon becoming attracted by the corresponding electromagnet, to swing said switch control member clear of the movable blade, thus permitting the latter to engage the said one fixed blade and thereby close the motor circuit to cause the operation of the motor and of the actuating mechanism for reciprocating the carriage; said mechanism having means for temporarily closing said motor circuit holding switch before the circuit first supplying current to the motor through the starter switch is opened, when the carriage,

moving in reverse direction, approaches its starting position and causes the starter switch control member to swing the movable blade away from said one fixed blade.

5. In an article ejector for vending machines of the type wherein articles of merchandise to be dispensed are stacked in upwardly moving columns, an ejector carriage reciprocatingly operative above the merchandise and being adapted to move from its starting position first in one direction and next in reverse direction and back to its starting position; means for actuating the ejector carriage in the aforesaid manner; a motor for driving said actuating means; said ejector carriage having a plurality of individually operable ejector elements corresponding in number to that of the merchandise columns, each ejector element having an article engaging portion and an extension; a detent for each element extension adapted to normally engage the latter for keeping the article engaging portion of the ejector element in elevated, inoperative position, a solenoid for each detent adapted, when energized, to attract the detent for disengagement from the element extension, thereby causing the article engaging portion to assume its operative position; a guideway for each article engaging portion of the element adapted to cause that portion to reassume its inoperative position when the carriage completes its first movement and before traveling in reverse direction.

6. In an article ejector as per claim 5, means for supporting and moving upwardly the merchandise in columns, an abutment extending upwardly from said means and being adapted to assume a position in the path of the article engaging portion of the ejector element when merchandise in the column served by that ejector element becomes exhausted, thereby retaining the

element in its inoperative position, and preventing the release of the element by the detent when the latter's solenoid becomes energized.

7. In an article ejector for vending machines of the type indicated, a reciprocating carriage having a plurality of individually operative ejector elements, each element consisting of an article engaging portion and an extension; a detent for each element extension for holding the elements in inoperative position, a double action starter switch having a movable blade operatively mounted between two fixed blades and adapted to bear towards one of the fixed blades; a switch blade holding member operatively mounted in and extending lengthwise said carriage and being adapted to normally press the movable blade against the other fixed blade; a stop for said holding member for limiting its movement; the extensions of all ejector elements being adapted, when released by their detents, to force said holding member to release said movable blade, thus permitting the latter to make contact with said one fixed blade.

8. In an article ejector as per claim 7, said ejector elements of the carriage being pivotally mounted and having spring means urging their article engaging portions to assume a downward, operative position; said detents retaining the elements by their extensions in an upward, inoperative position, against the tension of said spring means; said switch blade holding member having a bracket supporting a dielectric element adapted for engaging the movable switch blade, said holding member being pivotally mounted in said carriage, and a spring urging the holding member against said stop.

MARIO CARUSO.
